WALL TELEPHONE BASE

Jerry L. Schoemann, Glen Ellyn, and Martin J. Stevko, Addison, Ill., assignors to Automatic Electric Laboratories, Inc., Northlake, Ill., a corporation of Delaware

Filed Feb. 10, 1964, Ser. No. 78,574

Term of patent 14 years

(Cl. D26—14)

FIG. 1

FIG. 2

FIG. 3

FIG. 1 is a left side elevational view of a wall telephone base, showing my new design, the opposite side being substantially a mirror image thereof;

FIG. 2 is a front elevational view; and

FIG. 3 is a front, top and right side perspective view thereof.

The back, not shown, is unornamented.

The dominant features of my new design are shown in solid lines in the drawing. The broken line showing of a handset in FIG. 1 is for illustrative purposes only.

We claim:

The ornamental design for a wall telephone base, as shown and described.
